UNITED STATES PATENT OFFICE.

HARRY C. JONES, OF NEW YORK, N. Y.

METHOD OF AND APPARATUS FOR PRINTING.

Application filed November 5, 1925. Serial No. 66,896.

My invention relates to the method of and apparatus for printing, and more particularly for printing from a transparency onto a sensitized surface; and is especially 5 useful for photographic contact printing.

It is old to provide printing apparatus known as printing frames for contact printing, which consists in general of a rubber blanket having marginal flanges extending 10 around the same to engage a thick glass pressure plate so that a space is formed between the said pressure plate, the blanket and its marginal edges which engage the pressure plate; and this space so formed is 15 adapted to receive the entire sensitized surface, such for example as a sensitized zinc plate, and is also adapted to receive the negative from which the design is to be printed onto the sensitized surface of the zinc plate. 20 When the zinc and negative are placed within the space and the glass is latched down on the rubber blanket, air is exhausted out of the space to thereby cause a firm contact between the negative and the sensitized surface, and a print is made by suitable exposure to a light source. Such apparatus is 25 not adapted for contact printing in the case where it is impossible or undesirable to place the entire sensitized surface within the confines of the rubber blanket and glass pressure plate, or where no blanket can be used. Furthermore, such apparatus is very heavy and requires a very sturdy machine to handle it when it is being used.

Various other printing frames have been proposed in which a seal is formed between the printing frame proper and the sensitized surface and in each the photographic plate to be printed from is placed within the 30 confines of the seal and is adapted to be moved into intimate contact with the sensitized surface in various ways. This apparatus necessitates a rather heavy complicated structure which also makes it necessary to use 35 massive printing machines in order to properly handle these frames accurately. In addition to this, embossing of the thin zinc plate bearing the sensitized surface often results at points beyond the outer edges of the 40 photographic plate.

In cases where the design to be printed is carried on a thin flexible plate, such for example as a celluloid or gelatin transparency, it is usually customary to employ the 45 following method. The flexible transparency is mechanically pressed into intimate

contact with the sensitized surface by a member between which and the sensitized surface a vacuum is produced. Since the flexible member is within the space 60 from which the air is exhausted it is not acted upon directly and merely mechanically pressed between the members which are relatively moved together by vacuum means. 65

One of the objects of this invention is to 70 provide a suitable method of and apparatus for producing a more even and uniform contact between a member to be printed from and a member to be printed upon.

Another object of the invention is to 75 provide apparatus which may be handled with ease, and which may be provided at a small cost.

The invention consists in the method herein described and in the novel features, arrangement, construction and combination of the apparatus and means hereinafter described in accordance with certain preferred embodiments thereof, and the invention will be more particularly pointed out in the 80 appended claims.

Further objects of the invention will more fully appear from the following description taken in connection with the accompanying drawings illustrating, by way of example, 85 the preferred embodiments of the apparatus used in carrying out the method.

Referring to the accompanying drawings:

Fig. 1 is a plan view of one embodiment of the apparatus used in carrying out the 90 method.

Fig. 2 is a section taken at 2—2 of Fig. 1.

Fig. 3 shows a section of a modified form of Fig. 1.

Fig. 4 shows a section of another modification,

Fig. 5 shows a section of another modification,

Fig. 6 shows a section of another modification,

Fig. 7 illustrates a modified form of the apparatus, and,

Fig. 8 is a section taken at 8—8 of Fig. 7.

In photographic printing the design which it is desired to print may either be carried on a suitable substantially rigid plate such for example as a glass photographic plate; or may be carried on a flexible plate such as celluloid or gelatin; or any other suitable material such for example as tracing cloth, etc. The design to be printed may be photographically made and may be

either a "positive" or "negative"; or it may be made by any other suitable means. The design may be carried on a transparent medium or on a translucent medium; depending upon the strength of the light used in printing and the degree of sensitiveness of the surface upon which it is to be printed. Since the distinction between transparent and translucent is merely one of degree (a translucent body being semi-transparent), it is to be understood that where the term "transparent" or "transparency" is used, it is used in its generic sense and relates to bodies which allow sufficient light to pass therethrough to affect a photo-sensitive surface.

Referring to the drawings and more particularly to Figs. 1 and 2: a suitable frame 1 is provided for receiving a transparency 2, which in the present embodiment is shown as a glass photographic plate. A cover-like member 3, in the present instance made of resilient rubber, adapted to fit closely over the frame 1, comprises a downwardly extending body portion provided with an outwardly extending bead 4, and a resilient sealing portion having lips 5 and 6. In the present embodiment it is only essential that the top part comprising the sealing lips 5 and 6 be elastic, and therefore the lower body portion may be made of a non-resilient material. The lip 5 is adapted to encircle that portion of the transparency 2 to be printed from, and is adapted to contact with the upper face of the transparency 2; while the lip 6 is adapted to contact with the sensitized surface to be printed upon, such for example as the thin zinc plate 7 bearing a sensitized surface. The lip 6 is preferably cupped up, and both of the lips 5 and 6 are very thin and tapered to a feather edge, so that an efficient but thin seal is provided for the insertion between the transparency and the sensitized surface. It will therefore be seen that the member 3 provides means for centering, i. e. properly positioning transversely of the frame 1, and holding the plate 2 onto the frame 1, and also provides a sealing means which seals off the space 8. Suitable means is provided for attaching the member 3 to the frame 1, such for example as the toggle clamps 9 which are attached to the frame 1 and are adapted to engage the bead 4 to firmly and positively clamp the member 3 to the frame 1. However, when the member 3 is constructed to snugly fit the frame 1 and particularly where it is made of resilient material, the clamping means such as the toggles 9 are not essential, since suitable resilient means is thereby provided to hold the member 3 to the frame 1. Suitable lugs 10 are provided for handling the frame or for attaching it to a printing machine, where this is desirable.

65 A hole 11 is formed in the plate 2 within

the limits of the surrounding lip 5 and is adapted to communicate with a tube or pipe 12, which forms a means of communication between the sealed-off space 8 and a suitable air exhausting means, such for example as a 70 vacuum pump (not shown). The tube 12 is provided with a cupped sucker end 13 which permits the tube to make a good contact with the bottom of the plate 2, which will be designated as the outside of the plate 2 with 75 reference to the space 8. The tube 12 is also provided with a shut-off cock 14 which serves to close off the space 8 after the air has been exhausted and the vacuum pump disconnected. 80

In Fig. 3 a slight modification is shown, wherein the transparency or plate, which in this modification will be indicated as 2^a, is bevelled at its edges and is held to the frame 1^a by additional clamping means such for example as a plurality of clamps 15 attached to the frame by bolts 16. The centering and sealing member is designated as 3^a and a lip 5^a thereof which engages the plate 2^a is sufficiently long to extend over the clamps 15. 90 In this view, the air has been exhausted from the space 8 and the plates 2^a and 7 are shown in intimate face to face contact; the plate 7 having flexed slightly to allow for the thickness of the lips 5^a and 6^a. 95

Fig. 4 shows a slight modification of and is similar to Fig. 2, with the following exception; in this instance the transparency is shown as a flexible sheet or plate 2^b; and to prevent this flexible plate from being forced up against the plate 7 by the pressure exerted on the outside of the tube 12 while the air is being exhausted from the space 8, and thereby causing a resulting embossing of the plate 7, a bracket 17 is provided for rigidly holding the tube 12 to the frame 1. This bracket, therefore, rigidly holds the tube 12 in a predetermined position with respect to the plate 2^b. 100

Fig. 5 shows a slight modification of the structure shown in Fig. 3 and differs therefrom in the following respects. The additional clamping means in this instance are readily adjustable with respect to the frame 1^b and are constructed in the following manner. Brackets 18 are attached to the frame 1^b in the respective recesses 19 and arms 20 are pivoted respectively to the brackets 18 and are provided with bevelled upper end portions 21 adapted to engage the bevelled edge of the plate 2^b. The lower end of the levers 20 extend to the outside of the frame 1^b through suitable openings 22 formed in the centering and sealing member 3^b. The lower end of each of the levers 20 is threaded and is engaged by a suitable thumb screw 23 which is mounted in the frame 1^b free to be rotated with respect thereto, but held against axial movement. It will therefore be seen that by adjustment of the screws 23 120 125 130

the position of the plate 2^a may be adjusted with respect to the frame 1^b, before the plate 2^a is moved adjacent the sensitized surface or even after the member 3^b has been placed in position, but before the plate and sensitized surface have been brought into contact.

Fig. 6 shows a modification of Fig. 5 and differs therefrom in the following particulars. The frame 1^c carries a plurality of clamping members 20^a similar to the clamping members 20 above referred to, and these are adjustable by means of the thumb screws 23^a to properly position the plate 2^a with respect to the frame 1^c. The sealing means in this instance is designated as 3^c and comprises the lip portions 5^c and 6^c. The member 3^c is not adapted to be in any way attached to the frame 1^c but if desired may be attached directly to the marginal face of the plate 2^a by suitable means such as an adhesive.

Referring to Fig. 7, the zinc plate or sensitized surface 7 is represented as being a large surface onto a part only of which it is desired to print a design or image from a part only of the transparency 2^c. A resilient seal 3^c, such for example as that shown in Fig. 6, is placed around the design on that portion of the transparency to be printed from, and may be attached thereto by suitable means such as an adhesive if desired. The transparency is provided with a hole 11^c within the seal 3^c for purposes described hereinbefore. The transparency 2^c is then moved over that portion of the sensitized surface to be printed upon and then the seal 3^c is brought into sealing engagement with the sensitized surface; thereby forming a sealed-off space defined by adjacent inner faces of the transparency and sensitized surface and the seal 3^c, and including that portion of the transparency to be printed from and that portion of the sensitized surface to be printed upon. A communicating tube 12 is provided in a manner similar to and for purposes as described hereinbefore. Instead of placing the plate 2^c over the sensitized surface 7, the sensitized surface 7 may be placed over the plate 2^c. Also the two members 2^c and 7 may be placed in position with the seal 3^c between them, the important feature being the relative superimposing of the two plates with the seal between them and in contact with respective adjacent surfaces of the two plates. It will be obvious to those skilled in the art after understanding my invention that the transparent plate may be suitably registered with respect to the sensitized surface in various ways.

In the embodiment shown in Figs. 1-6 inclusive, the frame may be moved to the proper position with respect to the sensitized surface by hand. Suitable regis-

tion marks may be placed on the transparency and may be brought into alignment with suitable registration marks on the sensitized surface. Also the frame may be carried by a suitable carriage such as is common in photo-composing machines and may be brought into predetermined position thereby. Another way of obtaining proper registration would be to set the frame in proper approximate position and then adjust the transparency to the exact position by means of the adjustment means shown in Figs. 5 and 6.

Operation.

80

Referring to Figs. 1 and 2, the transparency 2 bearing the design to be printed is placed upon the frame 1, and the member 3 is placed in position as shown in Fig. 2 and is firmly secured to the frame 1 by the toggle clamps 9. This centers, i. e. transversely positions, the plate 2 with respect to the frame 1 and also holds the plate securely to the frame. The frame is now moved adjacent the zinc plate bearing the sensitized surface until the design carried by the plate 2 is in register with that portion of the sensitized surface to be printed upon and the lip 6 is then pressed against the sensitized surface. The tube 12 is placed over the hole 11 and the air is exhausted from the sealed-off space 8 formed over the design to be printed until the plate 2 and the plate 7 are forced into intimate contact. The zinc being fairly thin permits sufficient flexure to allow for the thickness of the sealing portion 5-6. The portion now in intimate contact is exposed to a suitable light source to thereby photographically print the design from the plate 2 onto the sensitized surface. The pipe 12 is open to the atmosphere thereby allowing air to re-enter the space 8 and permitting the frame to be removed for a subsequent printing.

In cases where the sensitized surface is too rigid to properly flex in order to accommodate the thickness of the sealing portion 5-6 a flexible transparency such as 2^b (Fig. 4) may be employed; in which case the flexible plate 2^b will adjust itself to the sensitized surface thereby producing intimate contact between the member to be printed from and the member to be printed upon.

It is, of course, obvious that a flexible plate such as 2^b may also be used in printing upon a flexible sensitized surface. One of the particular features of this invention is that such a flexible plate may be used without the danger of forcing the adjacent surfaces together adjacent that point where the air is being exhausted. This is of great importance in cases such as illustrated in Fig. 4 where a suitable means is provided to prevent this sucking together of the members 2^b and 7 over the sucker end 13. Where

130

such a flexible plate is used in printing upon a flexible sensitized surface, such for example as a thin zinc plate, the tube 12 is rigidly attached to the frame 1 in order to prevent the tube from being forced against the flexible plates by the resultant atmospheric pressure when the air is being exhausted from between the plates. It is to be understood, however, that the means (17) for holding the tube 12 is not restricted to use with a flexible transparency.

Referring to Fig. 5, the process of printing may be carried out as described in connection with Figs. 1 and 2, except that the plate 2^a may be adjusted transversely of the frame 1^b or 1^c when placed thereon, or even after the frame has been placed in appropriate position against the sensitized surface, the plate 2^a may be adjusted to bring it into more accurate registration with the sensitized surface.

In Fig. 6 the sealing means 3^c does not hold the plate 2^a to the frame 1^c but is adapted to act merely as a sealing means and additional holding means are provided in the form of the adjustable clamps 20^a.

Referring to Figs. 7 and 8, it will be noted that this application of the invention may be used in printing the entire design carried on a transparency, or may be used in printing a portion only of the design onto a portion only or all of a sensitized surface. In this embodiment the sealing strip 3^c, similar to that shown in Fig. 6, is inserted between the sensitized surface and the transparency encircling the portion to be printed and the air is exhausted from the space so formed to thereby bring the surfaces into intimate contact and the printing is then effected by subjecting the sensitized surface to a suitable light source.

In prior apparatus it has been necessary to continuously apply vacuum means to the printing frame while the adjacent surfaces of the sensitized surface and transparency are in contact. Due, however, to the flexibility of this invention the vacuum pump or other air exhausting means may be cut off in certain instances. For instance, in cases where it is desired to position the transparency in contact with the sensitized surface and then move the two surfaces to a suitable position to be supplied with the light source the shut-off cock 14 may be used to entirely close the sealed-off space after the air has been exhausted therefrom, and the tube 12 may then be disconnected from the vacuum pump or air exhausting means in order to permit free movement of the contacting transparency and sensitized surface to the position or location desired.

Having thus described my invention with particularity with reference to the preferred method of carrying out the same and in connection with suitable apparatus for carry-

ing out the same, and having referred to some of the possible modifications thereof, it will be obvious to those skilled in the art, after understanding my invention, that other changes and modifications may be made therein without departing from the spirit and scope of my invention, and I aim in the appended claims to cover such changes and modifications as are within the scope of the invention.

What I claim as new and desire to secure by Letters Patent is:

1. The method of printing from a transparency bearing a design to be printed onto a sensitized surface, which comprises placing an encircling sealing means between adjacent faces of said transparency and sensitized surface defining that portion to be printed and in contact with respective adjacent faces of said transparency and sensitized surface, thereby forming a sealed-off space, providing an opening extending from said space to the outside, exhausting the air from said space through said opening to thereby force the adjacent portions of said transparency and sensitized surface into intimate contact, and then printing the design from the transparency onto the sensitized surface.

2. The method of printing from a first plate bearing a design to be printed onto a second plate being a sensitized surface which comprises placing an encircling sealing means between adjacent faces of said plates defining that portion to be printed, and in contact with respective adjacent faces of said plates, thereby forming a sealed-off space defined by said plates and said sealing means, providing an opening through one of said plates extending from said space to the outside, exhausting the air from said space through said opening to thereby force the adjacent portions of said plates into intimate contact, and then printing the design from one plate onto the other plate.

3. In apparatus of the character described, the combination of a frame for receiving a first plate to be printed from onto a second plate bearing a sensitized surface, means for holding said first plate on said frame, and encircling sealing means adapted to be interposed between said sensitized surface and said first plate and provided with opposite faces adapted respectively to firmly contact with adjacent faces of said sensitized surface and said first plate, one of said plates being provided with an opening serving to place the space defined by said sealing means and said plates in communication with suitable vacuum means, and means of communication for exhausting the air from said space to thereby force the adjacent faces of said plates in intimate contact.

4. In apparatus of the character described,

- the combination of a frame for receiving a first plate to be printed from onto a second plate bearing a sensitized surface, means for holding said second plate on said frame, and encircling sealing means adapted to be interposed between said sensitized surface and said first plate and provided with opposite faces adapted respectively to firmly contact with adjacent faces of said sensitized surface and said first plate to thereby form a sealed-off space between said plates, one of said plates being provided with an opening extending from said space to the outside of said plate, means of communication for connecting said opening and space with suitable air exhausting means for forcing said plates together, and attachment means for rigidly holding said means of communication to said frame in a predetermined position with respect to said plate bearing said opening.
5. In apparatus of the character described, the combination of a support for receiving a transparency to be printed from onto a sensitized surface, and combined holding and sealing means adapted to jointly hold said transparency to said support and to lie between adjacent faces of said transparency and sensitized surface and surround a portion on said transparency to be printed from when said transparency and sensitized surface are relatively superimposed one with respect to the other, whereby a seal is formed between said plates surrounding that portion to be printed.
6. In apparatus of the character described, the combination of a support for receiving a first plate to be printed from onto a second plate bearing a sensitized surface, combined holding and sealing means adapted to jointly hold said first plate to said support and to lie between adjacent faces of said first and second plates and surround a portion on said first plate to be printed from when one of said plates is superimposed on the other of said plates, whereby a sealed-off space is formed between said plates including that portion to be printed, one of said plates being provided with an opening within said seal adapted to be placed in communication with suitable air exhausting means, and means of communication for exhausting the air from the sealed-off space provided between the first and second plate by said seal, to thereby force the adjacent faces of said plates into intimate contact.
7. In apparatus of the character described, the combination of a support for receiving a first plate to be printed from onto a second plate bearing a sensitized surface, combined holding and sealing means adapted to jointly hold said first plate to said support and to lie between adjacent faces of said first and second plates and surround a portion on said first plate to be printed from when one of said plates is superimposed on the other of said plates, whereby a sealed-off space is formed between said plates including that portion to be printed, and means of communication for exhausting the air from the sealed-off space provided between the first and second plate by said seal, to thereby force the adjacent faces of said plates into intimate contact.
8. In apparatus of the character described, the combination of a support for receiving a first plate to be printed from onto a second plate bearing a sensitized surface, combined centering and sealing means adapted to jointly center said first plate on said support and to lie between adjacent faces of said first and second plates and surround a portion on said first plate to be printed from when one of said plates is superimposed on the other of said plates, and clamping means for securely fastening said combined centering and sealing means to said support, whereby said first plate is held to said support and a seal is formed between said plates surrounding that portion to be printed.
9. In apparatus of the character described, the combination of a support for receiving a first plate to be printed from onto a second plate bearing a sensitized surface, combined centering and sealing means adapted to jointly center said first plate on said support and to lie between adjacent faces of said first and second plates and surround a portion on said first plate to be printed from when one of said plates is superimposed on the other of said plates, clamping means for securely fastening said combined centering and sealing means to said support, whereby said first plate is held to said support and a seal is formed between said plates surrounding that portion to be printed, one of said plates being provided with an opening within said seal adapted to be placed in communication with suitable air exhausting means, and means of communication for exhausting the air from the sealed-off space provided between the first and second plate by said seal, to thereby force the adjacent faces of said plates into intimate contact.

In testimony whereof I have signed my name to this specification.

HARRY C. JONES.
